(57) **CLAIM**

The ornamental design for a firearm accessory mount, as shown and described.

DESCRIPTION

FIG. 1 is a front, top, left side perspective view of a firearm accessory mount incorporating my new design;

FIG. 2 is a top plan view thereof;

FIG. 3 is a bottom plan view thereof;

FIG. 4 is an enlarged front elevation view thereof;

FIG. 5 is an enlarged rear elevation view thereof;

FIG. 6 is a left side elevation view thereof; and,

FIG. 7 is a right side elevation view thereof.

The uniformly broken lines shown in the figures represent portions of the firearm accessory mount that form no part of the claimed design.
